UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

BOLTLESS CAR SIDE.

1,093,840.

Specification of Letters Patent. Patented Apr. 21, 1914.

Application filed September 29, 1913. Serial No. 792,266.

To all whom it may concern:

Be it known that I, WILLIAM E. FOWLER, Sr., a citizen of the United States, and resident of Chicago, in the county of Cook and State of Illinois, have invented certain new and useful Improvements in Boltless Car Sides, of which the following is a specification.

My invention relates to railway cars and has particular reference to a novel metallic frame single sheath car, similar to that shown in my former Patent No. 962,425.

In the construction of cars known as the Fowler type; that is, metallic frame box cars having a single interior sheathing, the sheathing planks running longitudinally of the car, it is customary to attach the planks to the frame by means of bolts, the bolts projecting through slots punched in the frame.

Even if only every alternate plank is secured to the frame this requires a very large number of operations in punching the metallic members, which operations not only increase the labor cost but materially weaken the frame members. I have therefore conceived the idea of providing for means of securing the sheathing members in proper position and maintaining the same without punching any of the frame members. In practice it has been found not only desirable but essential that permanent means be associated with the car whereby the side planks may be kept in close relation to take up shrinkage and warping. One of the most efficient means is the inside strap extending from the top of the side planks down to the floor, a tightening nut finding a bearing on the flange of the side sill. I have conceived the idea of forming this tightening strap of

an angular shape whereby to provide suitable lateral stiffness using this strap as a side plank retaining means, this strap or angular member acting in place of the usual bolts which passed through the metallic frame members. Preferably this angular member is gained into the boards in order to provide a flush interior surface.

The invention will be more readily understood by reference to the accompanying drawings, wherein,

Figure 1 is a fragmentary transverse vertical section through a portion of a railway box car having my invention applied thereto; Fig. 2 is an enlarged sectional detail of

the upper end section; Fig. 3 is an inside elevation of the same; Fig. 4 is a section on the line 4—4 of Fig. 2; Fig. 5 is a section on the line 5—5 of Fig. 1; and Fig. 6 is a side elevation of a railway car constructed in accordance with my invention.

55

Referring more particularly to the drawings it will be seen that in a preferred application of my invention, the railway box car includes a side sill 10, a Z-bar top plate 11, frame posts 12 and a single interior longitudinally extending sheathing consisting of planks 13, placed edge to edge. As a means for entirely obviating the necessity

for punching slots or holes through the vertical frame members for securing the sheathing thereto, I provide an angular, preferably channel-shaped, interior post or tightening strap 14, this angular member being

set into the planks to provide a flush surface on the inside of the car. The flanges 70 of the channel are discontinued at the top whereas the web is continued and bent to form a hook which passes over the top plank 13. A pin 15, may be passed through the web of the channel and through the top 75

plank if desired. As a means for holding the top in position and at the same time permitting a vertical movement of the top plank I provide a casting having a top plate 16, and a downwardly extending leg 17, the leg 80

85 contacting the angular member 14, but permitting vertical movement thereof. This casting is secured by means of a bolt 18 to the web of the Z-bar top plate 11. At the bottom the angular member has riveted 90 thereto a round rod 19, with a threaded lower end, a nut 20, engaging therewith in order to exert downward force to tighten the sheathing. Preferably the rod 19 passes

95 through both flanges of the side sill 10, and thus secures the sheathing from inward movement at the bottom. The tightening strap and retaining posts such as described

100 form the sole retaining means for the sheathing and naturally obviate the necessity for punching the frame and boring the side planks. Thus the cost of a multitude of bolts is eliminated together with the labor cost in punching, boring and applying such bolts.

Furthermore, the cost of assembling 105 and repairing is much reduced and a practically boltless adjustable car side is provided.

Modifications may be made in the structure shown and such modifications as are within the scope of my claims I consider within the spirit of my invention.

5 I claim:

1. In a car side, the combination of metallic frame posts, an interior, longitudinally extending sheathing, said sheathing on the sides extending from door to end posts, 10 and means located interiorly of the car and extending from the upper portion of said sheathing downwardly through the floor of the car for securing said sheathing in place, substantially as described.
- 15 2. In a railway car, the combination of metallic frame posts, an interior, longitudinally extending sheathing, said sheathing on the sides extending from door to end posts, and a plurality of angular shapes located 20 on the inside of the car flush with the surface of the sheathing, such shapes extending from top to bottom of the car and acting to secure such sheathing in place, substantially as described.
- 25 3. In a railway car, the combination of metallic frame posts and an interior, longitudinally extending sheathing, said sheathing on the sides extending from door to end posts, an angular shape located on the inside of the car flush with the surface of the 30 car and acting as a means for securing such sheathing in place, and means for exerting downward force on said shape whereby to tighten said sheathing, substantially as described.
- 35 4. In a railway car, the combination of metallic frame posts, an interior, longitudinally extending sheathing, said sheathing at the sides extending from door to end posts, 40 and a plurality of interior removable posts, said posts acting as the sole means for re-

taining said sheathing against said frame posts, substantially as described.

5. In a railway car, the combination of metallic frame posts, an interior, longitudinally extending sheathing, said sheathing at the sides extending from door to end posts, 45 and a plurality of interior removable posts, said interior posts having a slideable connection with said frame posts, said interior 50 posts acting as the sole means for retaining said sheathing in proper relation in said frame, substantially as described.

6. In a railway car, the combination of metallic frame members, a single interior 55 sheathing, said sheathing extending from door to end posts and from side to side of the car across the ends, a plurality of flanged interior posts extending from top to bottom of the car and having a slideable connection 60 to said frame members, said flange posts acting as the sole retaining means for said sheathing, substantially as described.

7. In a railway car, the combination of metallic frame posts, an interior longitudinally extending sheathing, a bracket arranged interiorly of said car and secured to the plate thereof, a post located interiorly of said car extending from top to bottom thereof and acting as a means for securing said sheathing against said frame posts, the upper end of said retaining post 70 co-operating with said bracket and being retained against lateral movement thereby, 75 substantially as described.

Signed at Chicago, county of Cook and State of Illinois, this 26th day of September, 1913.

WILLIAM E. FOWLER, Sr.
